Patented Nov. 7, 1922.

UNITED STATES PATENT OFFICE.

EDWARD W. MENNIE, OF DETROIT, MICHIGAN.

COTTER-PIN EXTRACTOR.

Application filed February 24, 1921. Serial No. 447,563.

To all whom it may concern:

Be it known that I, EDWARD W. MENNIE, a citizen of the Dominion of Canada, and residing at Detroit, in the county of Wayne 5 and State of Michigan, have invented a new and improved Cotter - Pin Extractor, of which the following is a specification.

This invention relates to means for pulling out cotter pins which are so positioned as 10 not to be readily accessible, and its object is to provide a tool of this character which can be cheaply constructed, which will be strong and efficient in operation, and which cannot get out of order.

15 This invention is embodied in a pair of handles pivoted together, one of the handles having a pointed jaw adapted to enter the eyes of cotter pins, and the other handle having a jaw which serves as a fulcrum 20 member, the two jaws being adapted to swing past each other.

It also consists in bending one of the jaws so that its end is substantially parallel 25 to the axis of the handles.

25 It further consists in the details of construction illustrated in the accompanying drawing and particularly pointed out in the claims.

In the drawing, Fig. 1 is a side elevation 30 of the preferred form of cotter pin extractor having its pointed jaw engaging a cotter pin. Fig. 2 is an elevation of the jaws thereof when a cotter pin has been practically extracted. Fig. 3 is a plan of the jaws. Fig. 4 35 is a plan of a modification of this extractor. Fig. 5 is a side elevation thereof.

Similar reference characters refer to like parts throughout the several views.

The handles 1 and 2 of this extractor may 40 be of any desired size and shape, but I prefer to form one pointed and the other with a chisel end. The jaws beyond the rivet 3 may be in practical alinement with the handles, as indicated in Fig. 1, or at an angle thereto, 45 as indicated in Fig. 5. An essential part of the tool is a point on one jaw, whether it extends at right angles to or is parallel to the rivet.

In Figs. 1, 2 and 3, the jaw 4 is bent so that 50 the point 5 is substantially parallel to the

rivet 3. The end 6 of the jaw 7 is also bent across the end of the pointed jaw so that it may form a fulcrum in the general plane of the tool. When it is desired to remove a cotter pin 8 from a castellated nut 9, as indicated in Fig. 1, which is often very difficult to do because of the location of the nut, the point 5 is worked into the eye 10 of the pin, as shown in Fig. 1, after which the handles are brought together. The end 6 rests on 55 the nut 9 and acts as a fulcrum and the result is an easy and quick extraction of the cotter pin.

If the eye 10 were at right angles to the position shown in Fig. 1, the tool shown in 60 Figs. 4 and 5 may sometimes be of great value, especially when the work can alone be reached by a tool whose handles 11 and 12 are at right angles to the jaws. In this case, the jaw 13 is substantially straight and 65 pointed and the fulcrum jaw 14 has its end 15 bent to extend adjacent to the pointed end of the jaw 13.

In all of these forms, the jaws must be so formed that they may swing past each other 70 for otherwise the pins could seldom be entirely extracted from the mechanism on which the fulcrum jaw is resting.

It will be understood that the details and proportions of the various parts may all 75 be changed without departing from the spirit of my invention as set forth in the following claims.

I claim:—

1. A cotter pin extractor consisting of a 80 pair of handles pivoted together and jaws on the handles adapted to swing past each other as the handles are brought together, the end of one of the jaws being pointed, and the end of the other jaw being bent to extend 85 across beyond the pointed jaw.

2. A cotter pin extractor consisting of a 90 pair of handles pivoted together and jaws on the handles adapted to swing past each other as the handles are brought together, the end of one of the jaws being pointed, and the ends of both the jaws being bent to 95 overlap.

EDWARD W. MENNIE.
